CARD GAME APPARATUS

Jack Gordon, Brooklyn, N. Y.

Application January 19, 1933, Serial No. 652,538

4 Claims. (Cl. 35—8)

This invention relates to improvements in a card game apparatus.

An important object of my invention is to provide a card game apparatus in which one playing bridge or pinochle solitaire may reset all of the hands, after one or more plays have been made, with a minimum of effort.

Heretofore, in the art, no means has been provided whereby a bridge or pinochle solitaire player could reset the original hands in an instant and thus not break the continuity of his concentration on the particular problem of card playing that he is endeavoring to solve. For example, after a player has set the hands and the hands have been played or partly played, it frequently happens that the player finds that he has committed some strategical error, and in order to correct the same, it is often necessary for him to reset the hand and replay it until he discovers the error and corrects it. With my invention it is possible to immediately reset all of the hands, as soon as the player desires.

A further object of the invention is to provide in a manner as hereinafter set forth, a card game apparatus adapted to be carried in the pocket.

I accomplish these objects by means of the construction and arrangement hereinafter described and illustrated in the accompanying drawings in which:

Fig. 1 is a top plan view of a card game apparatus embodying my invention.

Fig. 2 is a section on the line 2—2 of Fig. 1.

Fig. 3 is a section on the line 3—3 of Fig. 1.

Fig. 4 is a front elevation of a card indicator used in my invention.

Fig. 5 is a top plan view of a modified form of my invention.

Fig. 6 is a section on the line 6—6 of Fig. 5.

In the drawings where for the purpose of illustration is shown a preferred embodiment of my invention, 10 is a rectangular shaped game board constructed of wood, cardboard or a suitable composition, having sides 11 and 12 attached thereto. The resultant structure is like that of a shallow box, the same being divided into nine compartments by means of the walls 13, 14, and 15, the latter being about one-half the height of the card indicators 16.

The card indicators 16 may be constructed of wood, cardboard or any other suitable material, and are of the general appearance as shown in Fig. 4. Card designations appear on both the front and rear faces of the card indicators in order that regardless of which face is turned up,

the player will be able to see what card is represented by the card indicator.

The compartments designated as 17 are adapted to hold the card indicators comprising each card playing hand. Each hand is identified by the notations North, South, East and West. Each one of the compartments 17 is provided with a series of guide rails 18 which are of the same height as the walls 13, 14 and 15. They are spaced apart in the compartments 17 the width 10 of the card indicators 16 in order that the latter may slide in the grooves formed by them.

When an apparatus for playing pinochle solitaire is desired, the apparatus will be constructed so as to provide two additional grooves in each 15 compartment 17, thus providing the room for the necessary card indicators for each pinochle hand.

The four compartments designated as 19, and the compartment designated as 20 may be utilized for keeping score sheets, pencils, erasers, 20 tobacco and the like.

Referring to Figs. 5 and 6, where a modified form of my invention is shown, the construction of the apparatus is the same, except that instead of using the guide rails 18 shown in Figs. 1 and 2, 25 I dispense with the same and use each card indicator as a guide rail, for the other.

When it is desired to play pinochle solitaire with the apparatus shown in Figs. 5 and 6, a different set of card indicators will be necessary 30 in order that 15 card indicators may fit into each compartment needed. The compartments could also be constructed so as to have a movable wall at one end thereof so as to increase the size of the same sufficiently to accommodate more 35 than thirteen card indicators. In that event card indicators for pinochle solitaire would be of the same size as those for bridge, if desired.

In the use of both of the forms of my invention, it will be observed that when the card indicators are played by bringing the same toward the player, they may be reset by merely tilting the game board or the frame away from the player, the card indicators sliding back to the unplayed position. Thus, with a minimum of 45 effort and in an instant the played hand or hands may be reset.

All of the forms of my invention can be made in miniature form adapted to be carried in the pocket. In that event the card indicators would 50 be moved into a played position by means of a pencil or some suitable instrument.

It is to be understood that the forms of my invention herewith shown and described are to be taken as preferred embodiments of the same 55

and that various changes in the shape, size and arrangement of parts may be resorted to without departing from the spirit of the invention or the scope of the claims hereunto appended.

5 Having described my invention, what I claim is:

1. In a card game apparatus, a game board comprising a flat rectangular base, side and end wall forming members secured to the base and upstanding partitions disposed transversely and lengthwise of the base and arranged between said members to provide a pair of spaced, endwise opposed, rectangular, central compartments and a pair of outer rectangular compartments centrally arranged in parallel spaced relation and overlapping the inner portions only of the central compartments, and a set of sidewise opposed slideable playing card indicators corresponding in number to the number of cards of a suit in a pack of playing cards arranged within each compartment, said sets bearing indicia corresponding to that of a deck of playing cards, the card indicators of each set normally abutting one side wall of the compartment for the set and selectively slideable when played to abut the other side wall of the said compartment and said game board capable of being tilted on a side thereof for simultaneously returning all of the played card indicators to normal position.

2. In a card game apparatus, a game board comprising a flat rectangular base, side and end wall forming members secured to the base and upstanding partitions disposed transversely and lengthwise of the base and arranged between said members to provide a pair of spaced, endwise opposed, rectangular, central compartments and a pair of outer rectangular compartments centrally arranged in parallel spaced relation and overlapping the inner portions only of the central compartments, and a set of sidewise opposed slideable playing card indicators corresponding in number to the number of cards of a suit in a pack of playing cards arranged within each compartment, said sets bearing indicia corresponding to that of a deck of playing cards, the card indicators of each set normally abutting one side wall of the compartment for the set and selectively slideable when played to abut the other side wall of the said compartment, said card indicators being of greater height throughout their length than said members, and partitions to facilitate the sliding thereof, and said game board acting to simultaneously return all of the played card indicators to an unplayed position when the same is tilted away from the player.

3. In a card game apparatus, a game board comprising a flat rectangular base, side and end

5 members secured to the base and upstanding partitions disposed transversely and lengthwise of the base and arranged between said members to provide a pair of spaced, endwise opposed, rectangular, central compartments and a pair of outer rectangular compartments centrally arranged in parallel spaced relation and overlapping the inner portions only of the central compartments, and a set of sidewise opposed normally removable slideable playing card indicators corresponding in number to the number of cards of a suit in a pack of playing cards arranged within each compartment, said sets bearing indicia corresponding to that of a deck of playing cards, the card indicators of each set normally abutting one side wall of the compartment for the set and selectively slideable when played to abut the other side wall of the said compartment, said card indicators being of greater height throughout their length than said members, and partitions to facilitate the sliding thereof, and said game board acting to simultaneously return all of the played card indicators to an unplayed position when the same is tilted away from the player.

4. In a card game apparatus, a game board comprising a flat rectangular base, side and end

10 members secured to the base and upstanding partitions disposed transversely and lengthwise of the base and arranged between said members to provide a pair of spaced, endwise opposed, rectangular, central compartments and a pair of outer rectangular compartments centrally arranged in parallel spaced relation and overlapping the inner portions only of the central compartments, and a set of selectively shiftable playing card indicators slidably mounted within each compartment and corresponding in number to the number of cards of a suit in a pack of playing cards, said sets bearing indicia corresponding to that of a deck of playing cards, the card indicators of each set normally abutting one side wall of the compartment for the set and selectively slideable when played to abut the other side wall of the said compartment, said game board capable of being tilted on a side thereof for simultaneously returning all of the played card indicators to normal position.
